(57) **CLAIM**

The ornamental design for an automotive heating and cooling panel, as shown and described.

DESCRIPTION

FIG. 1 is an isometric view of a bottom, front, and right side of an ornamental design for an automotive heating and cooling panel;

FIG. 2 is a front side elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The dashed broken lines are included for the purpose of illustrating portions that form no part of the claimed design.
